SOUND RECORDING SYSTEM

Chester M. Sinnett, Westmont, N. J., assignor to
Radio Corporation of America, a corporation of
Delaware

Application October 21, 1942, Serial No. 462,831

2 Claims. (Cl. 179—100.4)

My present invention relates to sound recording, and more particularly to monitoring of the recording process.

One of the main objects of my present invention is to provide a method of recording sound waves wherein a control tone is embodied in the sound record, and which control tone provides compensation during reproduction for changes in volume effected during the recording step.

Another important object of this invention is to provide a method of recording sound waves wherein a superaudible oscillator has its oscillations recorded on the record at the time of recording the audible frequencies, and the superaudible oscillation frequency being dependent upon adjustments made to a monitoring device.

Another important object of my invention is to provide a method of reproducing sound records wherein the record embodies a superaudible control tone for compensating for volume changes during recording; the superaudible control tone being utilized during reproduction of the sound record for varying the gain of the reproducing system in such a manner as to provide the aforesaid compensation.

Yet another object of the invention is to provide a method of automatic compression of the dynamic range during sound recording, and a superaudible control tone being employed to function as a reference frequency during reproduction whereby restoration of the original volume is effected.

Still other objects of my invention are to improve generally the efficiency and reliability of sound recording processes, and more especially to provide recording and reproducing systems wherein sound waves may be faithfully recorded and reproduced.

The novel features which I believe to be characteristic of my invention are set forth with particularity in the appended claims; the invention itself, however, as to both its organization and method of operation will best be understood by reference to the following description, taken in connection with the drawing in which I have indicated diagrammatically several circuit organizations whereby my invention may be carried into effect.

In the drawing:

Fig. 1 shows a schematic diagram of a recording method embodying the invention,

Fig. 2 illustrates graphically the characteristic of the superaudible oscillator in Fig. 1,

Fig. 3 schematically represents a reproducing

system employed for reproducing sound records made by the method of Fig. 1.

Fig. 4 shows schematically a dynamic range compression system employing the present invention.

Those skilled in the art are fully acquainted with the circuit details of the various networks which are to be described in the following figures. It is, therefore, not necessary to show such circuit details, and it is to be clearly understood that the following description is addressed to those skilled in the art of recording and reproducing sound records. In Fig. 1 the numeral 1 designates a source of audio frequency currents. Such a source may be a microphone, the detector of a radio receiver, the electrical pick-up of a record reproducer, or any other type of device providing audio frequency currents. The audio frequency currents are passed through a pre-amplifier 2 which may consist of one or more stages of audio frequency amplification. The amplified audio frequency currents may then be transmitted to a stage of audio frequency amplification 3 provided with a gain control mechanism. The numeral 4 designates an arrow. The latter is to be understood as schematically representing a gain control device. Such a gain control device, for example, could be a potentiometer for varying the control grid bias of the audio frequency amplifier. Indeed, any well known form of gain control device may be employed as a monitoring element at stage 3.

The purpose of the gain control, or monitor, device 4 is to permit the operator in charge of the recording process to cut down passages which are too loud, or to boost in volume those passages which are too soft. The functions of the monitor device are too well known to need further description. The monitored output of stage 3 is transmitted to a recorder amplifier 5. The output of amplifier 5 is applied to any customary and well known record-cutting instrumentality. Since there are many well known cutting devices, and different modes of cutting the sound track on the record, it is not necessary to describe such devices in detail. It is to be clearly understood, however, that the output of amplifier 5 may be applied to a film, tape or other recording means, if desired.

In addition to recording the monitored sound waves, according to my invention there is provided a reference, or compensation, wave on the record which has a frequency dependent in value upon the adjustments made to the gain control device 4. The reference wave is of superaudible

frequency, and is generated by a superaudible oscillator 6. The oscillator may be of the well known R-C type. Normal, or mean, frequency of the oscillator 6 is designated by the symbol F_c . Since the oscillator may be of any well known form, it is schematically represented. The oscillator tunable tank circuit is designated by numerals 7 and 8. These numerals denote the usual coil and variable condenser 8 which provide the tuning circuit of the oscillator. Of course, in an R-C oscillator the value of a resistor is usually varied to change frequency. The value of F_c can be chosen to be at any frequency above the range of audibility; say, for example, 17 kilocycles (kc.).

Merely by way of illustration, a dotted line is shown as connecting the gain control device 4 and the variable condenser 8. This dotted line is designated "Monitor control." It is to be understood that the monitor control is any mechanical coupling which varies condenser 8, or a resistance in case of an R-C oscillator, in accordance with adjustments of gain control device 4. Thus, adjustments of device 4 with respect to a predetermined normal amplification value is accompanied by predetermined variations in frequency of oscillator 6 with respect to the normal value F_c . It is to be understood that the amplitude of the superaudible oscillations will be constant at all times.

In Fig. 2 there is shown, in a purely qualitative manner, the relation between variations in gain of device 4 and the frequency of oscillator 6. It will be noted that for the frequency F_c the gain of network 3 is at a mean, or center, value. If the device 4 is adjusted to increase the gain of network 3, then the frequency of oscillator 6 will increase above F_c . On the other hand, if the device 4 is adjusted to lower the gain of network 3 below the normal value, then the frequency of the superaudible oscillations will decrease below the normal frequency value. Hence, it will be seen that any monitoring of the sound waves recorded on the sound record is accompanied by a simultaneous recording of a superaudible control tone whose frequency variation is a direct function of the monitoring variations. It is to be understood that the sense of frequency variation may be the reverse of that shown in Fig. 2. Furthermore, the variations of oscillator frequency may be performed by devices other than changes in the capacity of the tank circuits 7-8.

In order to reproduce a sound record which embodies the frequency-variable superaudible control tone there is employed a system as schematically shown in Fig. 3. Here the sound record and the record pickup device are not shown, since they are well known to those skilled in the art. Let it be assumed that the output of the pickup device is applied to a pre-amplifier 9. The amplified energy is composed of audible frequencies and the superaudible control tone frequency. Hence, the audio frequency filter network 10 is provided solely to pass audible frequencies, while the filter network 11 passes solely the superaudible control frequency.

The audio frequency energy output of filter network 10 is applied to an amplifier 12 which has a variable gain. The output of amplifier 12 is applied to a power amplifier 13, and any desired type of sound reproducer device, such as a loud speaker, may be connected to the output terminals of power amplifier 13. The energy at the output terminals of filter 11 is of superaudible frequency. In order to convert variations in frequency of the superaudible control tone into a

control voltage whose polarity and magnitude are respective functions of the direction and extent of frequency deviation of oscillator 6 from the value F_c , there is employed a discriminator-rectifier network 14. This network may be of any well known type employed as detectors of frequency modulation receivers, or as a discriminator of an automatic frequency control system of a superheterodyne receiver.

Usually the discriminator-rectifier 14 comprises a pair of rectifier circuits whose rectifiers are connected to have their rectified voltages in polarity opposition. The input circuits of the rectifiers are oppositely mistuned by equal frequency values from a predetermined mean frequency value. In the present case the latter frequency value may be F_c . It will, therefore, be seen that as the frequency of the oscillator 6 varies above or below F_c , there will be produced at the output terminals of network 14 in Fig. 3 an output control voltage which is positive or negative. The polarity will depend on the direction of frequency deviation of the control tone, and the magnitude of the control voltage will depend upon the amount of frequency deviation of the oscillator.

The control voltage is applied to a gain control electrode of amplifier 12. This manner of gain control is very well known. The gain control voltage will be applied to the amplifier 12 in a sense such as to compensate for the monitor control. Thus, if the monitor control had been adjusted to increase the gain above normal gain, the superaudible oscillation frequency would be increased above the value F_c . Hence, in the reproducing system of Fig. 3 the gain control voltage produced by the increase of control tone frequency above F_c would be a negative voltage. This negative voltage would be applied to the gain control electrode of amplifier 12, and would act to reduce the gain of the amplifier. Since the magnitude of the negative voltage would be proportional to the difference in frequency between F_c and the adjusted oscillator frequency, it is clear to see that the amplifier 12 would be reduced in gain to compensate for the monitor increase in gain.

It will now be seen that I have provided a control tone for record reproduction by means of which manual changes in volume during recording can be compensated for during reproduction. Generally, I record a superaudible frequency on the record at the time of recording the audible frequency, and the superaudible frequency is varied in accordance with variations of the monitor control. The control tone frequency variation is then reproduced, after being separated from the audible frequency, when the record is played. By passing the control tone frequency variation through a discriminator-rectifier circuit a compensation voltage is secured, and is used to provide changes in gain of an amplifier in the audible frequency path. In this way volume changes are returned to their original value as exist at the source 1.

If automatic compression is employed during sound recording, then the change in bias of the compressor network can be used automatically to change the frequency of the superaudible oscillator. In that case when the record is reproduced the original volume range can be restored. In Fig. 4 I have shown a system for securing an automatic compression. Here amplifier 20 is schematically represented as a controlled amplifier. Let it be assumed that this amplifier has a control electrode thereof subject to bias control

by the direct current voltage produced across the output load resistor 21 of a rectifier 22. A portion of the audio input to amplifier 20 is applied to rectifier 22. The voltage produced across output resistor 21 will then vary in magnitude in accordance with the modulation currents fed to amplifier 20.

The control voltage is applied in a negative, or gain reducing, sense to the gain control electrode of amplifier 20. Hence, as the audio amplitude increases, representative of increased volumes, there will be applied increased negative voltage to the amplifier 20. This reduces the dynamic range, and effects volume compression. The output of amplifier 20 may be applied to recorder amplifier 23, and the output of the amplifier 23 may then be recorded as explained above. Instead of utilizing a mechanical coupling to the superaudible frequency oscillator 6, there is employed an automatic control over the frequency of the tank circuit 7-8 of the oscillator. For this purpose there may be utilized any well known type of reactance tube network 30. The gain of the reactance tube is varied by means of the connection 31 to the negative end of rectifier output resistor 21. The function of the reactance tube is to simulate a reactive effect across the tank circuit 7-8 thereby causing F_c to change in accordance with the degree of compression. An R-C type oscillator may be advantageously employed in this case.

Those skilled in the art of frequency modulation transmission are fully aware of the manner of constructing a reactance tube circuit so as to provide a reactance effect across an oscillator tank circuit. For example, the control grid to cathode impedance of a tube may be connected across the tank circuit, while the control voltage connection 31 is made to the control grid of the tube. In this way the control grid to cathode capacity of a reactance tube is thrown across the tank circuit, and the magnitude of the capacity effected is a function of the voltage across resistor 21. Alternatively, the cathode to plate impedance of an electron discharge tube may be connected across tank circuit 7-8. A phase shifter element may then be employed to apply to the control grid of the reactance tube an alternating voltage which is in phase quadrature with the alternating voltage across tank circuit 7-8. In this case, the plate to cathode im-

pedance of the reactance tube has an inductive, or capacitative, effect dependent on the sign of the phase shifter element. Here, again, the frequency of network 7-8 may vary with respect to a mean frequency F_c depending upon the variations of the voltage across resistor 21 with respect to a mean value chosen to represent a normal gain of amplifier 20. Of course, the reproducing process will follow that described in Fig. 3.

While I have indicated and described several systems for carrying my invention into effect, it will be apparent to one skilled in the art that my invention is by no means limited to the particular organizations shown and described, but that many modifications may be made without departing from the scope of my invention, as set forth in the appended claims.

What I claim is:

1. In a system for recording sound waves, means for amplifying audio frequency currents derived from the sound waves, means for rectifying the currents to provide a control voltage, means to control the gain of the amplifying means with said control voltage, means to generate superaudible control oscillations, an electronic reactance device electrically associated with the generating means for control of the frequency of said superaudible oscillations, means responsive directly to said control voltage to vary the magnitude of the reactive effect of said electronic device whereby said superaudible frequency is varied, and means for recording both said amplified audio currents and said superaudible oscillations.

2. A method of recording sound waves while compressing the dynamic range thereof which includes amplifying audio frequency currents derived from the sound waves, deriving a control voltage from the currents controlling the amplification with said voltage in a manner which is inverse to the amplitude changes of the audio frequency currents, generating superaudible control oscillations, providing an electronic reactance to control the frequency of said superaudible oscillations, varying the magnitude of said electronic reactance with said control voltage thereby to vary the frequency of the oscillations in accordance with control of said amplification, and recording both said controlled audio frequency currents and control oscillations.

CHESTER M. SINNETT.
